UNITED STATES PATENT OFFICE

126,431

DESIGN FOR A COLLAPSIBLE TUBE

Donald Deskey, Annandale, N. J., assignor to
Bristol-Myers Company, New York, N. Y., a cor-
poration of Delaware

Application December 5, 1940, Serial No. 97,085

Term of patent 14 years

To all whom it may concern:

Be it known that I, Donald Deskey, a citizen of the United States, residing at Annandale, county of Hunterdon and State of New Jersey, have invented a new, original, and ornamental Design for Collapsible Tubes, of which the following is a specification, reference being had to the accompanying drawing, forming a part thereof.

In the drawing,

Fig. 1 is a front elevational view of a collapsible tube showing my new design.

Fig. 2 is a side elevational view of said tube.

Fig. 3 is a cross sectional view through the tube, along the line 3—3 of Fig. 1.

Fig. 4 is a top plan view of the tube, and
Fig. 5 is a transverse sectional view along the
line 5—5 of Fig. 1.

The characteristic feature of the design re-
sides in a tube of the configuration shown having
parallel ribs and depressions extending upwardly
from the smaller, flattened and tapered end there-
of and terminating at the lower edge of a smooth
band of frusto-conical form adjacent the upper
end of said tube, substantially as shown.

I claim:

The ornamental design for a collapsible tube,
as shown and described.

DONALD DESKEY.
